DESIGN FOR AN ADJUSTABLE PASSENGER
LOADING RAMP

Albert L. Varrieur, Baltimore, Md., assignor to
The Glenn L. Martin Company, Baltimore,
Md.

Application January 16, 1947, Serial No. 136,193

Term of patent 14 years

(Cl. D14—3)

To all whom it may concern:

Be it known that I, Albert L. Varrieur, citizen of the United States and resident of city of Baltimore, State of Maryland, have invented a new, original, and ornamental Design for an Adjustable Passenger Loading Ramp, of which the following is a specification, reference being had to the accompanying drawings, forming part thereof.

Figure 1 is a side elevation showing my new design of an adjustable passenger loading ramp.

Figure 2 is a front view thereof.

Figure 3 is a perspective view showing the ramp illustrated in Figure 1, with the adjustable portion extended.

Figure 4 is a perspective view of the ramp shown in Figure 1 in the collapsed position for moving and stowage.

Figure 5 is a plan view of the ramp shown in Figure 1 with the adjustable portion extended.

Figure 6 is a side elevation of the ramp shown in Figure 1 with the adjustable portion extended.

I claim:

The ornamental design for an adjustable passenger loading ramp, substantially as shown.

ALBERT L. VARRIEUR.
